US0D1016027S

(12) **United States Design Patent** (10) **Patent No.:** **US D1,016,027 S**
(45) **Date of Patent:** ** *Feb. 27, 2024

(54) **MOBILE PHONE**

(71) Applicant: **HUAWEI TECHNOLOGIES CO., LTD.**, Guangdong (CN)

(72) Inventors: **Jian Xu**, Shenzhen (CN); **Guoping Wu**, Shenzhen (CN)

(73) Assignee: **HUAWEI TECHNOLOGIES CO., LTD.**, Shenzhen (CN)

(*) Notice: This patent is subject to a terminal disclaimer.

(**) Term: **15 Years**

(21) Appl. No.: **29/816,513**

(22) Filed: **Nov. 23, 2021**

(30) **Foreign Application Priority Data**

May 25, 2021 (CN) 202130315841.2

(51) **LOC (14) Cl.** **14-03**

(52) **U.S. Cl.**

USPC ..... **D14/248; D14/138 C**

(58) **Field of Classification Search**

USPC ..... D14/138 G, 138 AD, 138 AB, 248, 341, D14/345, 439, 432, 371, 374, 138 R, D14/138 AA, 138 AC, 138 C
CPC H04M 1/0202; H04M 1/0235; H04M 1/0237; H04M 1/0239; H04M 1/0266; H04M 1/0268; H04M 1/027; H04M 1/0295; H04M 1/02; H04M 1/0279; H04M 1/0283

Primary Examiner — Bridget L Eland

(57) **CLAIM**

The ornamental design for a mobile phone, as shown and described.

DESCRIPTION

FIG. 1 is a front perspective view of a first embodiment of a mobile phone, showing our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a back perspective view thereof;

FIG. 9 is a front perspective view of a second embodiment of a mobile phone, showing our new design;

FIG. 10 is a front view thereof;

FIG. 11 is a back view thereof;

FIG. 12 is a top view thereof;

FIG. 13 is a bottom view thereof;

FIG. 14 is a right side view thereof;

FIG. 15 is a left side view thereof; and,

FIG. 16 is a back perspective view thereof.

The broken lines in drawings show portions of the mobile phone that form no part of the claimed design.

1 Claim, 12 Drawing Sheets
